TOOL HANDLE REMOVER

William D. Snowman, Pittsfield, Maine

Application June 19, 1944, Serial No. 541,093

1 Claim. (Cl. 29—242)

1

This invention relates to devices for removing broken handles from tools, such as axes, hammers or the like, and is an improvement over the construction embodied in my prior Patent No. 1,453,288, dated May 1, 1923, for Tool handle removers.

An object of this invention is to provide a handle remover embodying a base, means on the base for supporting the tool, a plunger or ejector guide, and a plunger or ejector slideable in the guide and adapted to force the broken handle from the tool when the ejector is struck by a hammer or other tool.

Another object of this invention is to provide a broken handle remover of this kind including an improved supporting member for the tool and means for firmly clamping the tool in a position whereby the broken handle may be readily removed therefrom.

With the foregoing objects and others which may hereinafter appear, the invention consists of the novel construction, combination and arrangement of parts as will be more specifically referred to and illustrated in the accompanying drawing, wherein is shown an embodiment of the invention, but it is to be understood that changes, modifications and variations may be resorted to which come within the scope of the invention as claimed.

In the drawing:

Figure 1 is a detail side elevation of a broken handle remover constructed according to an embodiment of this invention.

Figure 2 is a detail front elevation of the device.

Figure 3 is a vertical section taken substantially on line 3—3 of Figure 2, and

Figure 4 is a detail top plan of the device.

Referring to the drawing, the numeral 10 designates generally a base which is formed of a pair of parallel bars 11 and 12 which are secured to opposite end bars 13 and 14. The bars 11 and 12 are spaced apart and form a space 15 therebetween and within which the ejected handle is adapted to engage. An upright post or supporting member 16 extends upwardly from the rear bar 12 and is provided at its upper portion with a forwardly extending guide 17.

A forward or second post 18 extends upwardly from the forward bar 11 and has threaded therethrough a clamping screw 19 having a wheel 20 secured thereto. A pair of side bars 21 and 22 connect the rear and front posts 16 and 18 together at their lower portions, and the bars 21 and 22 are secured to these posts in any suitable manner and, in the present, by fastening bolts 23.

The bars 21 and 22 comprise supporting bars for supporting a block or anvil 24, and also comprise supporting means for a large tool head, such as an ax head, or the like. The block or anvil 24

is adapted to be positioned between the two posts 16 and 18 and is formed with an opening 25 which is adapted to be positioned beneath the guide 17 so that the broken handle which is ejected from the tool T may pass through the opening 25 and into the space 15. The block or anvil 24 is formed with a downwardly projecting key 26 engaging between the two bars 21 and 22 so as to hold the block or anvil 24 against lateral or endwise movement.

A rear plate 27 is carried by the forward side of the post 16 in a position confronting the screw 19 so that tightening of the screw 19 will cause the tool T to be clamped between the screw and the clamping plate 27. An ejector 28 in the form of an elongated rod is adapted to slidably engage through the guide 17 and to contact with the upper end of the broken handle H positioned within the tool T. Striking of the upper end of the ejector 28 will force the handle H downwardly through the opening 25 and into the opening 15 between the bars 11 and 12.

The screw 19 comprises a positioning and clamping screw to properly align the tool T beneath the guide 17 so that the ejector 28 will engage the upper end of the handle H.

In the use and operation of this broken handle remover, where the tool is small, such as a hammer head, the tool T is placed on the supporting block of anvil 24 with the handle H aligning with the opening 25 and with the guide 17. The ejector or plunger 28 is then lowered to a contacting position with the upper end of the handle H and the ejector may then be struck with a hammer or other tool, so as to forcibly move the broken handle from the tool handle socket. Where the tool is large, such as an ax head, the anvil or supporting block 24 is removed and the large tool head placed on the upper edges of the bars 21 and 22.

What I claim is:

A broken handle remover comprising a base formed with an opening to receive the ejected handle, a pair of upright posts rising from said base, a pair of spaced apart supporting bars fixedly secured to the outer sides of said posts adjacent the lower portions thereof, an ejector guide carried by the forward side of one of said posts, said one post being longer than the other post, a tool supporting block seated on said bars and having an opening aligning with said guide, a tool handle ejector slideable in said guide, a horizontal elongated clamping plate carried by the forward side of said one post and extending beyond the opposite vertical edges thereof, and a clamping screw threaded through the other post for tightly holding the tool against said plate.

WILLIAM D. SNOWMAN.
